ATTORNEY

UNITED STATES PATENT OFFICE.

KIJIRO FUKAGAWA, OF SAGA, JAPAN, ASSIGNOR TO MARUICHI-GOSHIKAISHA, OF TOKYO, JAPAN.

FERROREINFORCED-CONCRETE SLEEPER.

Application filed May 24, 1927, Serial No. 192,787, and in Japan December 20, 1926.

This invention relates to reenforced concrete railroad ties and has for its object the provision of a tie of novel and durable construction adapted to withstand the stresses and strains set up therein during the operation of railway rolling stock. My invention has as a further object the provision of novel fastening means for adjustably securing rails to the tie, whereby rails of different sizes and tracks of different gauges may be securely applied to the tie.

Thus, in accordance with my invention, I may provide a tie made of concrete and suitably reenforced by metallic rods to add rigidity and strength thereto. Furthermore, my tie may be made oblong and with dimensions similar to the present type of wooden ties, although I desire it to be understood that the tie may be made of any length depending upon the purposes for which it is to be used.

For a better understanding of my invention, reference is made to the accompanying drawings wherein:

Fig. 1 is an elevation of a tie in accordance with the invention,

Fig. 2 is a plan view of the tie,

Fig. 3 is a longitudinal sectional view of a portion of the tie taken on the line 3—3 of Fig. 2,

Fig. 4 is a cross sectional view of the tie taken on the line 4—4 of Fig. 2, and

Fig. 5 is a plan view showing the rail seat of the tie.

Considering the invention more in detail in connection with the drawings, my tie comprises an oblong body of concrete provided with recesses 1 and seats 2 for suitable rails 3. The recesses 1 serve to lighten the tie and cheapen the construction thereof without materially weakening it. Each seat 2 of the tie is provided with a pair of longitudinally disposed slots 4, as shown in Fig. 5, one side of each slot being open to the recess 1 on one side of the seat. Extending longitudinally from the bottom of each slot is provided a hole 4' communicating with the recess on the opposite side of the seat from that at which the slots are located. In other words, two L-shaped spaces comprising a slot 4 and hole 4' are provided in each seat.

Within these L-shaped spaces are arranged L-shaped fastening bolts 8, one leg of each of

the bolts being positioned in a slot 4 and the other leg of each of the bolts being positioned in a hole 4', as shown in Fig. 3.

On each of the seats 2 between the upper ends of the bolts 8 is adapted to be mounted a rail 3, held in position by means of clamping plates 6 and nuts 9 screwed on the upper ends of the bolts 8. The other end of each of the bolts 8 is provided with nuts 9'. The clamping plates 6 are of substantially U-shaped form and are provided at the extremity of their upper leg with a bent shoulder 5 adapted to engage with the base flange of the rail, when the plates 6 are in position on the bolts 8.

In mounting a rail on each of the seats 2, the L-shaped bolts 8 are placed in the slots 4, with one leg of each extending through the holes 4'. The clamping plates 6 are then placed upon the upper threaded ends of the bolts 8 and held down by nuts 9 while nuts 9' are applied to the lower ends of each of the bolts. By gradually tightening the nuts 9' and 9 the rails may be securely positioned at the desired point on the seat 2.

Because of the lateral adjustment provided by my form of tie and fastening means, it is possible to employ various sizes of rails in connection with my tie and equally possible to employ my tie in the construction of tracks of varying gauge. Particularly, is this feature of lateral adjustment of value where realignment of the rails is necessary after they have once been mounted and in use for some time. In the use of wooden ties it is necessary in such cases to remove the spikes and refasten the rail in its new position. With my form of tie it is merely necessary to tighten or loosen the nuts 9', as the case may be.

After mounting the rail upon the tie, its lateral position with respect to the tie can be accurately adjusted merely by screwing down the outer nut 9' of each seat to a greater extent when the rails are to be spread and the inner nut 9' of each seat to a greater extent when the rails are to be brought closer together. In each position of adjustment, the rails are securely held to the tie by virtue of the form of the clamping plates 6, which are adapted to engage the base flange of the rail and hold it securely in position regardless of whether the upper ends of the bolts 8 are

positioned relatively near or far from the edge of the rail.

Moreover, because of the length of the slots 4, the fastening bolts 8 may be adjusted longitudinally of the tie to conform with the width of the base flange of the rail without in any way impairing the mounting of the rail on the tie. In all positions the rail is securely retained upon the seat because of the tendency 10 of the bolts 8 to interlock upon the tightening of the nuts 9'. The rail and tie are thus held together in a most effective manner.

I claim:

1. A reenforced concrete railroad tie comprising a recessed body portion provided with rail seats, said seats having slots therein and passages extending from the bottoms of said slots through said seats.

2. A reenforced concrete railroad tie comprising a recessed body portion provided with rail seats, said seats having a slot in each side face thereof and a passage extending from the bottom of each slot through said seats longitudinally of said tie.

3. A reenforced concrete railroad tie comprising a recessed body portion provided with rail seats, said seats having a slot extending inwardly from each side face thereof longitudinally of said tie and a passage extending 30 longitudinally of said tie from the bottom of each slot to the opposite side face of said seat.

4. A reenforced concrete railroad tie comprising a recessed body portion provided with 35 rail seats, said seats having slots therein extending inwardly from each side face thereof

to a distance from the center of the seats less than one half the width of the base flange of a rail and passages extending from the bottoms of said slots through said seats.

5. A reenforced concrete railroad tie comprising a recessed body portion provided with rail seats, said seats having slots therein and passages extending from the bottoms of said slots through said seats, and fastening means 45 disposed in each of said slots and passages and adapted to engage the side faces of said seats, and the base flange of a rail mounted on each of said seats.

6. A reenforced concrete railroad tie comprising a recessed body portion provided with rail seats, said seats having slots therein and passages extending from the bottoms of said slots through said seats, L-shaped bolts seated in said slots and passages, clamping plates 55 mounted on the ends of said bolts extending from said slots, and nuts on the ends of the bolts extending from said passages.

7. A reenforced concrete railroad tie comprising a recessed body portion provided with 60 rail seats, said seats having a slot in each side face thereof and a passage extending from the bottom of each slot through said seat, an L-shaped bolt mounted in each slot with one leg of said bolt disposed in said slot and the other disposed in said passage, a substantially U-shaped clamping plate received on the leg of the bolt extending from said slot, a nut on said leg of the bolt, and a nut on the leg of the bolt extending from said passage. 70

In testimony whereof I affix my signature.
KIJIRO FUKAGAWA.
